Lauson & Associates(57) CLAIM

I claim the ornamental design for a handheld hookah, as shown and described.

DESCRIPTION

FIG. 1 is a perspective view of the handheld hookah.

FIG. 2 is a front view thereof.

FIG. 3 is a rear view thereof.

FIG. 4 is a left side elevation view, the right side elevation view being a mirror image; and,

FIG. 5 is a top plan view thereof.

The broken lines in the drawings depict portions of the hand held hookah that form no part of the claimed design.
